UNITED STATES PATENT OFFICE

WALTHER RASTER, OF CHICAGO, ILLINOIS, ASSIGNOR TO JUSTRITE MANUFACTURING COMPANY, OF CHICAGO, ILLINOIS, A CORPORATION OF ILLINOIS

DISPLAY CARD

Application filed January 24, 1930. Serial No. 423,034.

This invention relates to improvements in display cards for articles to be sold which are usually attached to such cards, and more particularly to display cards for that class of articles which are to be sold in lots rather than singly without being first detached from the card, the latter thus constituting a convenient carrier for the articles which may be slipped into an ordinary envelope when delivered to the purchaser.

The particular object of the invention is to provide a display card of the above-mentioned type which permits of easy assembly of the same with the articles to be displayed thereon and sold therewith and which, additionally, is equipped with a locking or latch element which serves to prevent detachment of the articles from the card until said latch or locking device has been removed.

20 The card of the present invention is designed and intended particularly to carry electric wiring clips and to so engage the clips that the latch or locking element above referred to may advantageously consist of a 25 piece of insulated wire or an imitation thereof which will, while performing its function as such latch or locking element, also serve to illustrate and demonstrate the manner of use of the clip.

20 In the accompanying drawings illustrating the invention:

Fig. 1 is a front or face view of a display card constructed in accordance with the invention.

35 Figs. 2, 3, and 4 are sectional views on the lines 2-2 and 3-3, respectively, of Fig. 1, the said Figs. 3 and 4 being identical with each other except that Fig. 3 shows a clip partly associated with the card and Fig. 4 40 shows the same in final position.

Fig. 5 is a fragmentary horizontal section on the line 5-5 of Fig. 1.

The display card of this invention is, as above indicated, intended to carry a plurality of electric wiring clips, each of which 45 comprises a flat shank 1, a curved formation 2, and a terminal lip 3.

In use, the shank 1 of the clip is adapted to be inserted between the base board or picture molding or other trim, and the plaster

wall of a room. It will be noted that the lip 3 is offset from the plane of the shank 1 so that in use, the latter will extend somewhat angularly to the plane of the wall upon which the lip 3 bears. Thus when the shank 55 is forced into the crack between trim and plaster, it will be flexed and thus frictionally held in place.

Prior to insertion of the shank as above described, the electric wire or cord to be held in place is engaged in the portion 2 of the clip.

This description of the said clip and the manner of its use is believed to be essential to a proper understanding and appreciation 65 of the advantages and utility of the said display card which consists of ordinary cardboard, such, for example, as is used in the manufacture of picture post-cards and the like.

The card 4 is provided with one or more, but usually a group of six sets of clip engaging formations. Each set of the latter consists of an inverted substantially U-shaped incision 5 which defines a tongue 6. Parallel with and spaced from the middle portion of the incision 5 is an incision 7. The portion of the card lying between the incisions 5 and 7 constitutes what I term a bridge-element 8. Above and spaced from the incision 7 is a rectangular opening 9, the top and bottom walls of which are parallel with the incision 7.

The portion of the card lying between the incision 7 and the opening 9 constitutes a 65 second bridge-element 10. The length of the incision 7 and the width of the tongue 6 and opening 9 are preferably identical with the width of the clip.

In use, the shank 1 of the clip is inserted 50 from the rear face of the card 4 through the incision 7 and then passes over the bridge-element 8 and underneath the tongue 6. The latter may, however, be omitted to provide a rectangular opening below the bridge- 95 element 8.

This movement of the shank 1 of the clip is continued until the portion 2 of the same passes through the opening 9 as shown in Fig. 4.

The clip is now firmly frictionally held in place on the card and, after the whole group of clips corresponding to the number of sets of said incisions, etc., has been similarly mounted on the card, a short piece of material 11 simulating insulated copper wire or flexible cord, is passed through the loop portions 2 of the clips and is secured to the card by cementing or other suitable means.

10 The clips are thus practically locked against removal from the card except by destroying the latter or marring it as by detaching the member 11, the latter performing simultaneously the aforesaid locking 15 function and, additionally, illustrating and demonstrating quite clearly the manner of use of the clips.

Obviously the specific details of construction of the display card may be modified and 20 varied to adapt the same for display of other articles without departing from the invention as defined in the appended claims.

I claim as my invention:

1. A display card for electric wiring clips 25 of the kind specified, equipped with an opening adapted to receive the loop formation of the clip, a pair of slots through which the shank of the clip is passed, and a retaining member secured to the card and spanning 30 said opening within the loop formations of said clips.

2. A merchandise package comprising a card provided with a series of sets of formations each including an opening and a pair 35 of parallel slots spaced from said opening, an electric wiring clip associated with each set of said formations and including a flat shank portion extending through and engaged in said slots, a loop or hook portion 40 projecting through said opening, and a lip portion, the latter and a part of said shank engaging the rear face of the card at opposite ends of said opening and said loop portion projecting from the front face of the 45 card, and a retaining bar spanning the several openings within the loop portions of said lip and secured to the front face of the card.

WALTHER RASTER.
